(57) CLAIM

The ornamental design for a photobook, as shown and described.

DESCRIPTION

FIG. 1 is a front perspective view of a photobook in a closed position with a photo strip on a front cover showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an inside perspective view of the photobook in an open position;

FIG. 9 is an outside perspective view of the photobook in said open position;

FIG. 10 is an outside view thereof;

FIG. 11 is an inside view thereof;

FIG. 12 is a right side view thereof;

FIG. 13 is a left side view thereof;

FIG. 14 is a top view thereof; and,

FIG. 15 is a bottom view thereof.

The broken lines in the drawings illustrate portions of the photobook which form no part of the claimed design.

1 Claim, 8 Drawing Sheets
